STRING TICKET ATTACHING DEVICE

Carl A. Flood, Framingham, Mass., assignor to
Dennison Manufacturing Company, Framing-
ham, Mass., a corporation of Massachusetts

Application October 31, 1933, Serial No. 696,017

28 Claims. (Cl. 112—104)

This invention relates to attaching materials or articles of the kind having a construction, composition and/or texture of such a character that they may be impaled or pierced as by passing a needle or similar instrument therethrough between surface portions or from one side to the other thereof, or by passing such instrument around or about portions of the article or material, which materials or articles have sufficient strength to be capable of retaining at least temporarily a flexible strand passing about or through portions thereof. Some materials of a comparatively dense compact composition may have relatively thin portions through which a needle may be readily passed while others may have openings adapted to receive a needle. Various articles of merchandise commonly have these characteristics, such for example as pieces of jewelry, textile materials including fabrics, garments and other articles of wearing apparel, also sheet materials whether woven or of irregularly matted fibrous construction; these are therefore representative of this general class of materials.

Prior methods of attaching string tags do not afford adequate protection against tampering or unauthorized transfer of tags. Moreover these prior methods have been uneconomical of string or other strand material employed. For instance, it is customary to use a tag which has been previously strung. The string may be threaded through a hole in the tag and the ends tied together to form a continuous loop or the ends of the string may be passed between the plies of the ticket to form a closed loop. Such a tag is usually attached to an article by looping it through or over some suitable portion of the article such as through a buttonhole of a garment or over a button. Sometimes a hooked needle is used to pull the string through a portion of the fabric and then the tag is threaded through the loop formed by the string which has passed through the fabric. In all of these instances the string must be long enough to form a loop of such size that the tag may pass through it. Also the tag may be easily removed or shifted to another article by reversing the process.

This invention provides for attaching price tags to material and is also useful for attaching mated articles such for example as a pair of stockings or a pair of gloves. In some aspects the invention pertains to a method and to a device for passing a flexible strand, as a cord or string through a ticket and an article and uniting portions of the strand to form a closed loop which secures the ticket to the article. While such a device may assume various forms it is highly desirable that it should be of such compact and efficient construction that it is not only portable, but may be conveniently carried in and operated by one hand of an operator

while the other hand is left free to manipulate materials or articles to be ticketed. This requires a construction and relative arrangement of parts which in addition to providing for efficient mechanical operation, also produces a good balance and thus contributes to efficient use. Moreover it is frequently advantageous to be able to attach price tickets in such a way that they may be easily removed by a purchaser and yet the unauthorized transfer of a ticket from one article to another will become apparent immediately upon inspection. The present invention provides for accomplishing this objective by attaching the ticket with a loop of strand material which loop is formed by clenching about the end portions of the strand a clip which is so small especially when clenched that it can not be removed without special tools. The clip may be formed of metal which is capable of bending as required during the clenching operation and yet so brittle that if any attempt is made to spread the clenched clip to remove it, it will break. On the other hand anyone authorized to remove the tag may do so easily by cutting the strand.

Objects of the invention are to improve the art of attaching tickets by providing methods and means for attaining the aforementioned desirable objectives; to provide for attaching tags and the like to articles by means of a flexible strand in a manner which will not require the separate operations of first stringing the tag and then the subsequent operation of attaching it to an article but will simultaneously insert the string through both the tag and the article; to provide for securely attaching a tag or the like with a loop which need not be long enough to permit the tag to pass through it; and also to provide a device for these purposes having an improved construction and relative arrangement of parts.

In the drawings:

Fig. 1 is a top plan view of a device for attaching tickets to material;

Fig. 2 is a left-hand elevation of the device shown in Fig. 1;

Fig. 3 is a right-hand elevation of the device shown in Fig. 1;

Fig. 4 is a bottom plan view, to an enlarged scale, of the device shown in Fig. 1;

Fig. 5 is a front elevation, to an enlarged scale, of the device shown in Fig. 1;

Fig. 16 is a section similar to Fig. 11 with the parts in different relative positions;

Fig. 17 is a section on the line 17—17 of Fig. 16 illustrating the relative position of the parts as a fastening element or clip is clenched;

Fig. 18 is a section similar to Fig. 9 but showing the parts in different relative positions;

Figs. 19 and 20 are detail sectional views similar to Fig. 16 and illustrating the parts in different relative positions to show the manner in which the fastening elements are clenched and separated from their supply strip;

Fig. 21 is a sectional view similar to Fig. 9, illustrating a relative position of the needle and of the strand catching and retaining device;

Fig. 22 is a section on the line 22—22 of Fig. 21;

Figs. 23 and 25 are sections similar to Fig. 21, but showing the parts in different relative positions;

Figs. 24 and 26 are views similar to Fig. 22 but showing the parts in positions corresponding to those shown in Figs. 23 and 25, respectively;

Fig. 27 is a side elevation, with parts omitted and broken away, of a device similar to the one illustrated in the preceding figures, but embodying automatic means for shifting the slide or latch plate;

Fig. 27a is a plan view of the front or forward portion of the slide or latch plate of the device shown in Fig. 27;

Figs. 28, 29 and 30 are fragmentary side elevations similar to Fig. 27 but showing the parts in different relative positions;

Fig. 31 is a top plan view of an attaching device similar to the devices illustrated in the preceding figures, but embodying a knot tying mechanism for uniting portions of the strand;

Fig. 32 is a left-hand side elevation of the device shown in Fig. 31;

Fig. 33 is a right-hand side elevation, to an enlarged scale, of the device shown in Figs. 31 and 32 with parts omitted and broken away; and

Figs. 33a and 33b are detail views illustrating in left-hand elevation parts of the knot tying mechanism of Figs. 31 to 33 in different relative positions.

The device selected for illustration in Figs. 1 to 26 of the drawings comprises a frame, indicated generally at 10, and formed of right and left mating parts 11 and 12 shaped to extend rearwardly so as to provide a hollow handle grip 13, the forward portion of the frame extending vertically in the form of a rectangular post 14. This post has a slideway which conveniently may be formed in one of the mating parts, as in the left-hand part 11, as indicated at 16, this slideway being adapted to receive and guide a needle slide

17. This slide has a laterally projecting arm or head 18 to which a needle 19 is secured in any approved manner, as by being fitted in a cylindrical recess or hole and secured therein by means of a set screw 21. Intermediate its ends this slide has a transverse recess 22, and at its lower end the slide is provided with an inclined cam surface 23 which terminates in a vertically extending slot 24.

The lower end of the composite frame post 14 fits within the vertically disposed flanges or side plates of a channel-shaped member 26, the transverse web of this channel being spaced below the lower surface of the post 14 to form therewith a guide passage or channel for a reciprocatory 15 clenching die plate 27 (Figs. 11 and 12). At its forward lower end the post 14 is fitted with a clenching die block 28 having a curved channel or guideway 29 for delivering clips to the clenching die. Forwardly of the channel 29 the die block is 20 provided with a groove 25 (Fig. 5) having convex side walls which diverge outwardly to form a flaring guideway for directing strands into the channel 29.

This clenching die block has a downwardly ex- 25

tending lug or projection 31 (Figs. 11, 12, 12a, 16, 19 and 20) which extends through a slot 32 in the clenching die plate 27 and into a slot 30 in the base of the channel member 26. The slot 32 is of a length to permit the desired reciprocatory move- 30

ment of the clenching die plate 27. The forward end of this slot is adapted to function as an anvil 35

surface for clenching a clip about pieces of strand material, such as string or the like. This forward end portion of the slot joins a narrower slot 33 35

providing an entrance through which the string to be clipped may be introduced. Preferably the forward end portion of the plate 27 is formed to diverge from the narrow slot 33 to provide guide 40

surfaces 34 for directing strands into the slot 33. Below the plate 27 the forward edge of the projection 31 is cut away or beveled at 35 to provide 45

clearance for removal of clenched clips. The forward end of the slot 30 is located so close to the projection 31 that an unclenched clip can not pass 45

through this slot as the material forming the slot projects inwardly and forms shoulders or abutments 40 which effectively engage the legs of unclenched clips. These shoulders or abutments 40 serve as stops which due to this engagement de- 50

termine the position of an unclenched clip. The forward end of slot 30 joins a slot 33' which is similar to, although wider than slot 33 in plate 27. The base of the channel member 26 is cut 55

away from slot 33' along lines 34' which diverge preferably from a point inwardly of that from which lines 34 diverge even when the movable plate 27 occupies its extreme right-hand position as shown in Fig. 16. The die block 28 is secured 60

between the flanges of the channel member 26 by suitable fastening elements, such as the screws 36 (Fig. 2), and the channel-shaped member 26 is secured to the lower end portion of the post 14 by similar fastening elements 37.

Clips are supplied in strip form to the clench- 65

ing die through a chute or enclosed channel 38, which extends through the hollow handle 13 from a suitable reel or spool 45' or other source of supply.

Preferrably the handle 13 is equipped at its rear- 70

ward extremity with a magazine 39, which may be substantially cylindrical and which may be separated by a partition member 41 into a com- 75

partment 42 for flexible strand material, and a compartment 43 for a reel of clip elements. A

post 44 may be mounted in this partition member 41 and arranged to extend through these compartments to provide a support for the reel in each compartment. Conveniently these chambers or 5 compartments 42 and 43 may be in the form of substantially cylindrical closure members having their end walls apertured to fit over the post 44 and equipped with pivotal latch members 9 which are receivable in grooves (not shown) in the post 10 for releasably retaining the closure members in position. This partition member 41 may extend forwardly beyond the magazine and beneath the handle 13 in the form of a web having a lower edge 46 constituting an abutment, and the forwardly extending portion of this partition may be secured between the adjacent mating portions of the handle 13 as by means of an attaching screw 47, which secures these portions of the handle and partition together.

20 A spool 45 of flexible strand material, such as string, may be mounted upon post 44 in compartment 42, and the strand may be threaded through an arcuate thread guide 48 on the handle 13, and over a spring tension guiding device 49 on the 25 head 18 of the needle slide from which the strand may be threaded through the needle.

An operating member or lower handle 51 (Figs. 2 and 3) is provided with a forked or bifurcated forward end, the furcations of which embrace 30 the channel-shaped member 26 and are mounted to pivot on a pivot screw 52, which extends through and is carried by the lower portion of the post 14. A bell-crank in the form of a latch member 53 is mounted on this same pivot, with sufficient friction so as to remain in various positions to which it may be moved. A link 54 is pivotally connected to the upwardly extending arm of the bell-crank 53, and this link carries at its forward end a transversely disposed cutter or knife 56. 40 A bracket 57 mounted on the forward side of the post 14 extends forwardly above and closely adjacent to the knife or cutter bar 56. This bracket is equipped with a flat spring 58, which is bent downwardly and rearwardly to engage and bear 45 against the under surface of the cutter bar 56, for the purpose of holding this cutter bar snugly against the under surface of the laterally projecting portion 55 of the bracket 57. This laterally projecting portion 55 of the bracket is provided 50 with a hole 59 (Fig. 18) to permit the needle to pass freely through this bracket.

A lever arm 61 (Fig. 11) is mounted to pivot on the pin 52 and carries a lower projection 62 which fits within a similarly shaped hole or recess 63 55 in the reciprocating clenching plate 27. This arm 61 is provided at its rearward end with a rectangular notch 64. A presser foot 66 is mounted to pivot on a pin 65 on the right-hand side of the device, as shown in Fig. 3. This 60 presser foot is in the form of a curved lever having a transversely extending portion 67 adapted to engage and compress material. The lower portion of the lever below the pivot carries a pin 68 which projects inwardly into a recess in the frame. 65 As shown in Fig. 11, the lower portion of the post 14 is provided with a transverse bore or passage 69, and a coil spring 71 is disposed in this passage and bears against the adjacent end surface of the clenching block 28, and also bears against a 70 headed pin 72 which engages the pin 68 carried by the curved lever 66 of the presser foot. These parts are so arranged that the spring 71 tends normally to rotate the presser foot and its engaging surface 67 in a clockwise direction as viewed 75 in Fig. 3. The lower portion of the post 14 is

inclined downwardly to provide a surface or bed 73 (Fig. 11) to receive superposed pieces of material, and the presser foot serves to clamp such pieces of material against the surface 73.

Mechanism for operating the cutter 56, the presser foot 66 and the needle slide 17, comprises a pair of levers 74 and 76 mounted to pivot on a pin 75 (Figs. 1, 2 and 3), these levers being spaced from each other by a spacer member 77, which is rigidly secured to both levers by attaching elements 78 so as to prevent relative movement of the levers. The forward end of the lever 74 has a round extremity which fits within the transverse recess 22 of needle slide 18. The forward end of lever 76 is pivotally connected to a link 79 (Fig. 3) which extends to the presser foot lever 66. This presser foot lever carries a lug having a transversely disposed head 81, the shank of this lug being disposed within a slot 82 formed in the forward end of the link. 20 These parts are so constructed and arranged that when the lever 51 is in the position shown in Figs. 2 and 3, the link 79 engages the presser foot lever 66 through the medium of the lug 81, and holds this presser foot retracted or spaced 25 above the opposing material-receiving surface 73 of the post 14.

A link 83 (Fig. 2) is pivotally connected to the upper arm of the bell-crank latch member 53 and to the cutter bar link 54 by the pin 84. 30 The free end of this link is slotted to receive a pin 86 carried by the lever 74 (Fig. 2), this pin and slot connection being so proportioned and arranged as to move the pin 84 and the cutter bar link 54 forwardly or to the left, as viewed 35 in Fig. 2, as the lever 74 is moved in a counter-clockwise direction. This pin and slot connection 86 is also proportioned to maintain the pin in the slot of the link 83 as the lever 74 returns to the position shown in Fig. 2, so as to permit 40 the lever 74 to return to this position without actuating the cutter bar link 54. The lever 51 is yieldably urged to return to the position which it occupies in Figs. 2 and 3 by means of a re-tracting spring 87, which is connected to a hook-like projection 88 formed on the lever 76, and to a pin 89 mounted upon the forward end of the lever 51, as shown in Fig. 3.

The clenching die operating lever 61 (Fig. 11) is connected by a link 91 with a bell-crank lever 92 (Fig. 2) which is mounted to pivot on the screw 93 carried by the post 14. The lower arm of this bell-crank lever 92 is adapted to engage 50 the upwardly extending arm of the bell-crank latch member 53 when these parts occupy certain 55 relative positions (Fig. 15).

The clenching die block 28, (Figs. 2 and 11) is provided with a vertical passage 96 which is disposed to one side of the clip-guiding channel 29, the passage 96 being in alignment with and adapted to receive the needle 19. This passage also extends laterally from the path of the needle to the adjacent side flange of channel member 26 (Fig. 14). At the upper end of passage 96 the die block is provided with a V-shaped notch 8 which is disposed adjacent the groove 25 so that strands held in passage 96 may be drawn taut through this notch and into groove 25 and the clip-guiding channel 29. The lower portion of the frame post 14 is provided with a transverse recess to receive a reciprocating strand catcher and gripper element 97 (Fig. 9). This element is in the form of a rectangular plate or bar which extends longitudinally of the device and carries a pin 98 which extends lateral- 70 75 76 77 78 79 80 81 82 83 84 85 86 87 88 89 90 91 92 93 94 95 96 97 98

ly from both sides of the gripper element. On the left side of the device this pin extends through a slot 99' in the adjacent flange of the channel-shaped member 26, this pin being adapted to be engaged by the lower arm of the bell-crank latch member 53. The plate member 97 (Figs. 9 and 13) is provided with a longitudinal recess adapted to receive a spring 98' which bears against one end of the recess and against the frame surface 99 so as to tend normally to urge the gripper plate 97 to the left as viewed in Figs. 9 and 13. The upper forward end of this gripper plate carries a projecting lug or loop catcher 101 (Fig. 13). The gripper plate 97 is also provided with a slot 102 to receive the frame attaching element 37 (Fig. 2) and to provide for freedom of movement of this gripper plate with respect to the element 37. This gripper plate 97 is disposed adjacent and to one side of the path of the needle 19 as shown in Fig. 10 and the forward vertical edge 103 of this plate is arranged to be parallel with the opposing vertical edge 104 of the clenching block 28 for clamping strand material against the latter edge.

The lower, pivotally mounted handle 51 is provided with a longitudinal recess 106 (Figs. 3 and 15) and a reciprocating slide or latch plate 107 is mounted on the upper side of this handle above the recess 106. A suitable attaching element such as a screw 108 is secured to the handle 51 and extends through a slot 109 in the slide 107 for securing the latter to the handle 51. The slide 107 carries a pin 110, which projects downwardly into the recess 106 where a spring 111 seats against the pin 110 and against the end of the recess 106 so as to tend normally to urge the slide plate 107 rearwardly or to the left as viewed in Fig. 3. This slide plate carries a forwardly and laterally extending grip plate 112 (Figs. 1 and 2) to provide for convenient manual operation of this slide plate. When the slide plate occupies its normal position, as shown in Fig. 3, the rearward end of this plate closes a vertical passage 113 through the handle 51. A post 114 is mounted to pivot on a transverse pin 116 secured to the rearward ends of the levers 74 and 76. The forward end of the latch plate 107 is receivable within the rectangular notch 64 of the clenching die plate actuating lever 61. The lever 51 also carries at its rearward end an adjustable stop in the form of a screw 117 which is adapted to engage the superposed abutment 46 provided by the forwardly extending web portion of the partition member 41. Engagement of the screw 117 and the abutment 46 serves to limit upward movement of the lever 51.

Preferably the strand attaching elements for use with this device are supplied in the form of substantially U-shaped metallic staples or clips 118 (Fig. 6) which are similarly disposed along a narrow strip or ribbon of severable sheet material 119, such as paper, to which the clips may be secured by a coating of adhesive 121. The paper provides a flexible connection between the clips and thus makes it possible to wind the connected clips on a spool or reel and to deliver such clips through irregular or curved passages. As the paper strip which forms this connection is easily torn, the individual clips may be readily separated and the paper remaining on each clip after separation from the strip provides a soft pad against which flexible strand elements 122 (Fig. 8) may be pressed and into which such strand elements may be substantially embedded and

thereby effectively secured by the legs or prongs of each clip during the clenching operation without danger of severing such strand elements between sharp metallic edges on the prongs and on the back or base portion which connects these prongs and toward which the prongs are bent when clenched.

Preferably these clips are formed of material which is capable of bending sufficiently to undergo the clenching operation without rupture and which is brittle enough to break when an attempt is made to spread a clenched clip to loosen the strand disposed therein. This effectively prevents unauthorized transfer of tags from one article to another as well as the unauthorized attachment of a tag to any article since unauthorized persons will have neither the clips nor the means of attaching them.

Moreover, irrespective of whether these fastening elements or clips have this peculiar characteristic, after being clenched, of sufficient brittleness to break before separating, it is preferred that the individual clips should be comparatively minute when clenched and preferably so small in size that when a clenched clip is held securely between the thumb and forefinger of a man's hand the clip can not be grasped securely between the thumb and forefinger of the left hand without releasing the grip of the right hand. It is found that when clips are of these small proportions it is practically impossible to open a clenched clip without the aid of tools which are especially adapted for this work and such tools would not ordinarily be in the possession of unauthorized persons. Furthermore it is believed that the use of clips so difficult to remove especially where the removal requires great care and something more than ordinary aptitude in the use of special tools, will effectively discourage tampering with price tags.

The device described herein with reference to Figs. 1 to 20 is intended to be held in and operated by the right hand of an operator, while materials to be attached, such as a price tag or ticket and a piece of fabric are supplied to and removed from the device with the left hand. In using this device the palm of the right hand is placed across the upper handle 13 with the thumb of this hand extending downwardly along the left side of the device (the side illustrated in Fig. 2) in a position conveniently to engage the laterally extending grip plate 112 of the slide or latch plate 107. The fingers of the right hand are extended downwardly along the right side of the device (the side illustrated in Fig. 3) and about the movable handle or operating member 51 to grip the latter for imparting a necessary motion to this handle. With the device held in this manner the materials or articles to be attached, such as a marking tag or ticket T and a piece of fabric F, are arranged in superposed relation, preferably with the ticket uppermost, and placed upon the supporting surface or bed 73, as illustrated in Fig. 11. It will be understood that as the fabric and the ticket are placed in this position the parts are in the relative positions illustrated in Figs. 1 to 5. The movable handle or operating member 51 is then moved upwardly without disturbing the position of the grip plate 112 or its associated slide or latch plate 107 so that as the handle 51 is advanced upwardly the slide or latch plate 107 projects across the passage 113 (Fig. 3) and provides an abutment or support for the post 114. This upward movement of the handle, therefore, is imparted through the post 114 to the levers 74 75

and 76 and no movement is imparted to the lever arm 61. As the lever 74 swings about its pivot in a counterclockwise direction, as viewed in Figs. 2 and 9, the needle slide 17, due to its connection with the forward end of this lever, is moved downwardly from the position shown in Fig. 2 to the position shown in Fig. 9. This same movement of the handle 51 causes the lever 76 to move in a similar manner and at the beginning of the movement of this lever the link 79 is advanced from the position shown in Fig. 3 to permit the presser foot arm 66 to be swung in a clockwise direction as viewed in Fig. 3, by its actuating spring 71 (Fig. 11). The parts are so proportioned and arranged that the presser foot arm is released sufficiently by the link 79 to swing to the position shown in Fig. 11, wherein the transversely disposed arm or foot proper 67 engages the superposed sheets of material and presses them firmly against the supporting surface or bed 73, as shown in Fig. 11, before the needle slide has descended far enough to cause the needle to pierce the sheets of material. These sheets, therefore, are firmly held in position when they are first engaged by the descending needle 19. Also at the beginning of the downward movement of the needle slide the knife or cutter 56 is moved from the position shown in Figs. 2 and 3 to the position shown in Fig. 9 in which it will be noted that the knife has been moved forwardly sufficiently to clear hole 59 in bracket 57 and to be out of the path of the descending needle. This movement of the knife is effected by the link 83 which is connected between the lever 74 and the link 54 which actuates the knife. As the needle slide continues its downward movement, the needle 19 passes through the hole 59 in the bracket 57 and pierces the ticket T and fabric F, as shown in Fig. 9, and passes downwardly into the passage 96. Approximately as the needle enters the passage 96 the cam surface 23 of the needle slide engages the portion of pin 98 which extends on the right side of the gripper plate 97 and this continued downward movement, therefore, is effective due to this engagement, to move the gripper plate 97 substantially to the position shown in Fig. 9 in which the forward end of this gripper plate and its projecting lug or loop catcher 101 is retracted to the rear of the path of the needle and the strand carried thereby. The movable handle or operating member 51 is then released and allowed to return to the position shown in Figs. 2, 3 and 13 and is caused to return to this position by the retracting spring 87. During this returning movement of the handle the retractile spring 87 through its connection with the levers 74 and 76 is effective to move the needle slide upwardly to the position of Figs. 2 and 3 and at the beginning of this upward movement it will be seen that the cam surface 23 permits the gripper plate to move forwardly or to the left, as viewed in Fig. 9, and as the handle returns toward its normal position the presser foot arm 66 is retracted against the action of its actuating spring 71 due to the connection of the arm 66 with the lever 76.

The action of the gripper plate 97 is illustrated in Figs. 21 to 26. Figs. 21 and 22 show the relative position of the parts when the needle is at the limit of its downward movement. As the needle slide moves upwardly (Figs. 23 and 24) the strand S carried by the needle is held sufficiently by engagement with the fabric and the ticket to cause a loop L to be thrown into the path 75 of the gripper plate as illustrated in Fig. 24 and

at this point the forwardly projecting lug or loop catcher 101 of the gripper plate 97 has advanced slightly within the loop thus formed. In Figs. 24 and 25 the needle has been withdrawn from the ticket and the fabric, the pin 98 has been released by the cam surface 23 and the gripper bar 97 has been moved by its spring to the left, as viewed in Fig. 25, to a position in which the loop catcher 101 projects entirely through the loop L and into a recess 100 while the forward surface 103 of the gripper plate 97 firmly engages and presses the loop L against the opposing surface 104 so that the loop is firmly held in the position shown in Figs. 25 and 26.

In attaching tags to articles of jewelry, hardware, and the like, as for example, in securing a ticket about the bail of a pail, if the ticket has a hole to receive the needle and the strand there may be substantially no resistance to withdrawal of the strand as the needle is withdrawn. In such cases the loop L may be considerably narrower, but there will always be a portion of the strand of this loop in the path of the gripper element 97 so that the latter will function to retain the strand.

While it is not necessary to the operation of this device it is preferred to use a needle 19 of the type having a relatively long straight groove 19^a leading from the eye of the needle along the shank on the side thereof to which the strand is carried from the tension device 49 while the opposite side of the needle is provided with a comparatively short groove 19^b which is not long enough to receive the strand on this side of the needle at the point where the latter passes through the ticket and fabric when the needle is at the limit of its downward stroke as illustrated in Fig. 9. The strand at this point therefore is pinched or squeezed against the needle by the material of the ticket and fabric and as the needle is withdrawn this portion of the strand is effectively held by its engagement with the ticket and fabric so that the smooth shank of the needle easily slides by it. This assists in forming the loop which is caught by the loop catcher 101 of the gripper bar. The short groove 19^b receives the strand as the needle is piercing the ticket and fabric and thus functions definitely to locate or position this portion of the strand and also to make it easier to pierce the ticket and fabric.

In the next operation the operator grasps the ticket T and fabric F and draws it outwardly away from or transversely of the path of the needle and in so doing causes the strand S to be drawn through the needle. The portion of the strand extending below the ticket and fabric to passage 96 is drawn into the V-shaped notch 8. This forms a loop L', Fig. 15, extending through the ticket T and the fabric F. In drawing out the strand to form this loop the hole 59 in bracket 57 serves as a guide which relieves the needle of lateral strain. The loop L' is drawn into the converging ways provided by the groove 25 and the surfaces 34 of the clenching die plate 27 which direct this loop through the narrow slot 33 into the forward end of the larger slot 32.

At this time the lowermost clip has descended from the clip channel 29 into the slot 32 of the 70 clenching die plate 27 with the prongs or legs of the clip extending forwardly and disposed solidly against the shoulders or abutments 40. As the loop L' is drawn through the narrow slot 33 into the larger slot 30 the strands of the loop are posi- 75

tioned within the prongs of the clip which rests against abutments 40.

In order to unite the ends of the loop the ticket and fabric are held below the device in a manner 5 to draw taut the strands of the loop as illustrated in Fig. 18. The operator then presses the grip plate 112 forwardly and in so doing moves the slide or latch bar 107 forwardly so that it no longer obstructs passage 113 and therefore 10 leaves the post 114 free to pass through this passage in the handle. However, this forward movement of the latch plate brings its front portion into the rectangular notch 64 in arm 61, and thereby effects a rigid connection between 15 these parts (Figs. 15 and 16). Upward movement of the handle therefore does not actuate levers 74 and 76 but does move arm 61 upwardly. This arm through the link 91 swings bell-crank 92 in a counter-clockwise direction, as viewed in 20 Fig. 15, so that the lower arm of this bell-crank engages the upper arm of bell-crank 53 and moves the latter clockwise and thereby moves link 54 and cutter 56 to the right, as viewed in Fig. 15. This movement brings the cutter across hole 59 25 in bracket 57 and severs the strand. This same movement of the lower bell-crank 53 also releases the strand which up to this time has been held by the gripper bar. The lower arm of bell-crank 53 functions as a latch or cam and is 30 formed with an upwardly extending extremity or toe 53' which provides a cam surface adapted on upward movement to engage and retract pin 98 which is carried by the gripper bar 97. It will be 35 seen that this retracts the gripper bar to the position shown in Fig. 21 in which the strand is released. Preferably the parts just described are so proportioned and arranged that the strand is cut by the knife 56 just before the lower end of the strand is released by the gripper bar.

40 The same upward movement of handle 51 unites the ends of loop L' by clenching a clip about these portions of the strand. From Figs. 11 and 16 it will be seen that as the handle 51 and arm 61 move upwardly the clenching die plate 27 is moved 45 rearwardly by the lug 62 of arm 61. The plate 27 moves from the position shown in Fig. 12^a to that shown in Fig. 17 and during this movement the end portions of slot 32 engage the prongs of the clip 118 and clench these prongs firmly about 50 the strands of the loop L'. The handle 51 and grip plate 112 are then released and the parts return to the positions shown in Fig. 18 in which it will be noted that the slide 107 has been returned by spring 111 to a position beneath the 55 post 114 ready to actuate the levers 74 and 76 on the next operation. To detach the clenched clip from the next adjacent unclenched clip in the supply channel it is only necessary to pull the loop L' downwardly rather sharply. The 60 clenched clip passes freely through the end portion of slot 30 in the channel member 26 (Fig. 19) while the impact of the prongs of the unclenched clip against the abutments 40 (Fig. 20) is sufficient to tear or break the paper connecting these clips and also serves definitely and accurately to position the unclenched clip for the next clenching operation. When the fabric and ticket are removed from the device they are secured together by the strands of the loop L' 65 which are firmly attached by the clenched clip.

70 The paper which remains within the clenched clip serves a very useful purpose. During the clenching operation the clip rests solidly against the die block 31 and the prongs must be brought 75 to bear against the strands of the loop with

sufficient pressure to prevent these strands from slipping after the clip is clenched. Without this paper or similar backing it would be very difficult and probably impracticable to attempt to secure this necessary pressure engagement without causing the prongs at least partially to sever the strands against the back of the clip. The paper, however, forms a protective pad which makes it possible to secure a good grip on the strands without requiring great precision in the clenching 10 operation.

From the foregoing it will be seen that the device thus far described herein operates in two cycles. During the first cycle the ticket and fabric are yieldably gripped by the presser foot 15 under the action of the spring 71 which automatically compensates for variations in thickness of material. The needle pierces the ticket and fabric and is withdrawn and the strand is caught and held by the gripper bar. During the 20 next cycle the loop L' is formed and its ends are united by clenching a clip about its strands, the lower end of the strand forming the loop is released by the gripper bar while the upper end thereof is severed adjacent the needle. The 25 clenched clip is then detached from the series of clips by severing the connecting paper strip. The operations of each cycle are performed by actuating the handle 51 but in one case the slide or 30 latch plate 107 is at the rearward limit of its movement while in the other, this slide is at the forward limit of its movement.

The device illustrated in Figs. 27 to 30 is identical with the one described herein with reference to the preceding figures with this exception, that 35 it is adapted automatically to shift the slide or latch plate between its two operative positions and thus to cause the device to function alternately on one cycle and then on the other. This is accomplished in an efficient and comparatively 40 simple manner by adding only a few parts which do not add appreciably to the cost of the device. In this embodiment a link 126 is pivotally connected to the upper arm of bell-crank 53 and is 45 mounted to pivot about the screw 93 which also constitutes the pivot for the upper bell-crank 92. A wire spring 127 is secured to the upper end of link 126. This spring extends downwardly 50 along the link 126 and is secured at its lower end to an extension 128 formed on or carried by the slide plate 107. The grip plate 112 employed in the previous form of the device is omitted. A knob 129 is mounted on the upper arm of bell-crank 53 preferably at the pivotal connection of this member and link 126. 55

The device is shown in Fig. 27 with its parts in position for the first cycle of its operation. As the handle 51 is moved upwardly the link 83 moves the bell-crank 53 in a counterclockwise direction (Fig. 28). This swings the link 126 60 clockwise and flexes the spring 127 in a manner to cause it to tend to move the latch plate forwardly. However, the post 114 bears upon the rear end of the latch plate with sufficient pressure to hold this plate from forward movement 65 until the handle 51 is released and returns substantially to the position shown in Fig. 29 and at this position the spring is effective automatically to move the latch plate into the notch 64 of arm 61, as shown in Fig. 29. The device is now set 70 for the second cycle of its operation.

On the next upward movement of handle 51 the upper bell-crank 92 moves the lower bell-crank 53 clockwise. This swings the link 126 to a position to flex or bow the spring 127 to the 75

form shown in Fig. 30, i. e., in the opposite direction from that shown in Fig. 28 so that the spring now tends to move the latch plate 107 rearwardly and it accomplishes this result as soon as the 5 handle 51 returns substantially to the position shown in Fig. 27 and the post 114 is withdrawn from its position behind the latch plate.

While this device is entirely automatic in shifting from one cycle to the other it is also capable 10 of manual control. As previously pointed out herein the lower bell-crank 53 is mounted with sufficient friction to remain in positions in which it is set. This action is assisted in this modification by the action of the spring 127. If the 15 device is set for one cycle of operation and the operator desires to perform the other it is merely necessary for him to push the knob 129 between the position in which it is shown in Fig. 27 and its position in Fig. 28. This sets the device for 20 the desired cycle of operation.

The embodiment illustrated in Figs. 31 to 33^b has the same first cycle of operation and the parts which function during this cycle may be and 25 preferably are the same as in the devices described herein with reference to the preceding figures. However, in this last modification the specific means for uniting the strands are in the form of a knot tyer of the general type disclosed 30 in the patent to Colman, No. 672,636 to which reference may be had for a better understanding 35 of the principles and mode of operation of this knot tying device. As this knot tyer includes a knife which severs the strand automatically, the 40 knife 56 and its associated parts, as shown in preceding figures of the drawings, are omitted. Since 45 no fastening elements are used with this device the clip guiding passages and magazine may be omitted. The handle portion 12' is provided on its rear end with a cup member 130 which carries 50 the reel post 44' and receives the casing member 42' which encloses the spool of strand material 45 and is releasably secured to post 44' by latch 9.

As shown in Figs. 31 and 32 the tying bills 131, 45 132, the knife 133 and the rotary operating shaft 134 are mounted in a cam cylinder 136 which provides a bearing for the rotary shaft and includes an internal cam 137 for operating the knife. This cylinder is provided with a reduced 50 threaded portion 138 which extends through and is clamped against a bracket 139 by a nut 141 which has threaded engagement with the portion 138. The bracket 139 is mounted upon the frame of the device in any approved manner as 55 by means of attaching screws 142 (Fig. 33). A small spur gear 143 is fixed upon shaft 134 and meshes with a gear sector 144 carried by an arm 145, which is pivotally mounted upon the frame by a screw 146. The gear sector arm 145 extends 60 rearwardly beyond its pivot and at its rear end it has a pivotal connection 148 with a link 147 which is mounted to pivot at 149 on arm 61. It will be understood that this arm 61 functions as described with respect to forms of the device previously disclosed herein. Also the lower projecting 65 end of bracket 57' has been cut away in the form of a notch 151 which diverges from hole 152 to provide a guideway for directing the strand into this hole. It will also be evident from this 70 disclosure that the automatic shift-over mechanism of Figs. 27 to 30 may be embodied in this form of the device if desired.

In using this device the operations of the first cycle are performed in the same manner as in the 75 other forms of the invention previously described

herein. To perform the second cycle of operations the grip plate 112 is moved forwardly as before to connect the movable handle 51 with the arm 61. The strands forming the loop L'' are drawn forwardly and transversely across the tying bills 131, 132 of the knotter as illustrated in Figs. 31 and 32; these strands are also guided by the notch 151 and hole 152 which are positioned to bring adjacent portions of the strands substantially together. As the movable handle 10 51 is moved upwardly arm 61 also moves upwardly and causes the link 147 to move slightly, as indicated by dotted lines in Fig. 33, to actuate the gear sector 144 through an arc sufficient to rotate gear 143 and therefore the tying bills and their 15 associated cutter through a complete revolution. This ties the knot and severs both strands of the loop. The dot and dash lines in Fig. 33 illustrate the relative positions of the parts when the handle 51 has moved upwardly through three 20 quarters of its stroke and the tying bills have rotated through 270°. Fig. 33^a is a left-hand elevation illustrating this position of the tying bills and cutter and showing the arrangement of the strands which form the knot and which are 25 about to be severed. Fig. 33^b is also a left-hand elevation but shows the parts in the positions corresponding to that illustrated in full lines in Fig. 33 in which the handle 51 has moved upwardly through its full stroke and the tying bills and 30 cutter have made a complete revolution from the position in which they are shown in Figs. 31 and 32. It will be understood that the strands are severed as the knotter turns from the position shown in Fig. 33^a to that shown in Fig. 33^b. The 35 knot is stripped from the tying bills manually. The portion of the strand which is held by the gripper bar and its loop catcher is also released during this latter portion of the stroke. Since both strands of the loop are cut by this knotter, a 40 piece of strand material 153 (Fig. 33) is discharged by the device.

During the first three quarters of the stroke this piece 153 extended between the tying bills and the passage 96 where it was retained by the 45 gripper bar. The term "pierce" is used herein and in the claims in its broad sense to include passing the needle or a strand through any portion of an article or material as well as passing a 50 needle or strand through openings within the body of an object or piece of material or passing the needle or strand about narrow objects or pieces of material.

It should be understood that the present disclosure is for the purpose of illustration only and 55 that this invention includes all modifications and equivalents which fall within the scope of the appended claims.

I claim:

1. The combination of opposed members, a single needle carried by one of said members, the other of said members being spaced from the needle to receive material to be ticketed, the latter member having a passage to receive the needle and the strand carried thereby, yieldable 60 means for holding superposed pieces of material against the latter member in the path of the needle, means for effecting relative movement of said members toward and from each other for passing the needle and its strand through material and into said passage and for withdrawing the needle, retaining means for holding the strand in said passage as the needle is withdrawn, and uniting means operable after each withdrawal of the needle to unite portions of the strand 70 75

which are then disposed between said passage and the withdrawn needle, said retaining means being releasable after operation of the uniting means.

5 2. The combination of opposed members, a needle carried by one of said members, the other of said members being spaced from the needle to receive material to be ticketed, the latter member having a passage to receive the needle and the 10 strand carried thereby, means for effecting relative movement of said members toward and from each other for passing the needle and its strand through material and into said passage and for withdrawing the needle, means for holding the 15 strand in said passage as the needle is withdrawn, means for uniting portions of the strand disposed between said passage and the needle, and a member disposed adjacent the uniting means, the latter member having a groove providing converging surfaces for receiving and drawing strand portions together adjacent the uniting means.

20 3. The combination of a needle having a flexible strand threaded therein, means for effecting 25 relative movement of material to be ticketed and the needle to cause the latter to pierce the material to carry the strand therethrough, means for uniting portions of the strand extending from opposite sides of the material, an operating member 30 for actuating both of said means, means effective on operation of one of said means for rendering the operating member effective on the next actuation thereof for operating the other of said means, and selectively operable means for 35 rendering said operating member effective for actuating either of said first-mentioned means.

4. The combination of a needle having a flexible strand threaded therein, means for effecting relative movement of material to be ticketed and 40 the needle to cause the latter to pierce the material to carry the strand therethrough, means for uniting portions of the strand extending from opposite sides of the material, an operating member 45 for actuating both of said means, a shiftable member for connecting the operating member to one or the other of said means, a resilient member connected with said shiftable member, and means effective on operation of one of said means for tensioning said resilient member to cause the 50 latter to tend to shift said shiftable member to connect the operating member with the other of said means.

5. The combination of a needle having a flexible strand threaded therein, means for effecting 55 relative movement of material to be ticketed and the needle to cause the latter to pierce the material to carry the strand therethrough, means for uniting portions of the strand extending from opposite sides of the material, an operating member 60 for actuating both of said means, a shiftable member for connecting the operating member to one or the other of said means, a resilient member connected with said shiftable member, means effective on operation of one of said means for 65 tensioning said resilient member to cause the latter to tend to shift said shiftable member to connect the operating member with the other of said means, and selectively operable means for rendering said operating member effective for actuating either of said first-mentioned means.

70 6. The combination of opposed members movable relatively toward and from each other, a needle carried by one of said members, the other of said members having a passage to receive the 75 needle and the strand carried thereby, means for

holding the strand in said passage as the needle is withdrawn, means for uniting portions of said strand disposed between said passage and said needle, operating means for effecting relative movement of said members and for actuating said strand uniting means, and selective means for rendering said operating means effective only for actuating said strand uniting means. 5

7. The combination of opposed members, a needle carried by one of said members, the other 10 of said members being spaced from the needle to receive material to be ticketed, the latter member having a passage to receive the needle and the strand carried thereby, means for effecting relative movement of said members toward and from each other for passing the needle and its strand through material and into said passage and for withdrawing the needle, means for holding the strand in said passage as the needle is withdrawn, means for uniting portions of the strand 15 disposed between said passage and the needle, a lever for effecting relative movement of said members to insert and withdraw the needle and also for actuating said strand uniting means, and selective means for rendering said lever effective 20 only for actuating said strand uniting means.

8. The combination of opposed members, a single needle carried by one of said members, the other of said members being spaced from the needle to receive material to be ticketed, the latter 30 member having a passage to receive the needle and the strand carried thereby, releasable means for holding said material in the path of the needle, means for effecting relative movement of said members toward and from each other for passing the needle and its strand through material and into said passage and for withdrawing the needle, retaining means for holding the strand in said passage as the needle is withdrawn, said 35 releasable means releasing the material as the needle is withdrawn and means for uniting portions of the strand disposed between said passage and the needle following each withdrawal of the needle, whereby the material may be moved from said retaining means and needle to bring string 40 portions into juxtaposition, and the juxtaposed string portions may be engaged with the means for uniting the same. 45

9. The combination of a needle having a flexible strand threaded therein, means for effecting 50 relative movement of material to be ticketed and the needle to cause the latter to pierce the material to carry the strand therethrough, means for uniting portions of the strand disposed on opposite sides of the material, the latter means 55 comprising clenching mechanism, means for conducting a series of clips to the clenching mechanism, abutment means engageable with an unclenched clip for stopping the latter in position for clenching, means for directing strands to be 60 united into an unclenched clip in said position, and means providing a passage for discharge of clenched clips, the unclenched connected clips being adapted to be advanced into position for 65 clenching by pulling united strands to move the clip clenched thereon through said passage and to bring the next adjacent unclenched clip against said abutment means with sufficient impact to break the connection between this unclenched clip and the clip just clenched about these strands. 70

10. The method of the class described which comprises conducting a series of connected unclenched clips to clenching mechanism and locating the foremost clip of the series in position for clenching by engaging only the projecting prongs 75

- of this clip to stop the latter in this position, 5
clenching this clip about strand material and
then, while preparing to stop the next clip in the
same manner by engaging only the prongs there-
of, pulling the strand material and the clip
clenched thereon with such force that the re-
sulting impact on the unclenched clip breaks the
connection between the clenched and unclenched
clips.
- 10 11. The method which comprises conducting a
plurality of connected unclenched clips to a
clenching station, stopping the foremost un-
clenched clip in position for clenching by engag-
ing at least one of the projecting prongs thereof,
15 clenching this clip and removing it from the
clenching station with such force that the con-
nection between this clip and the adjacent un-
clenched clip is broken substantially as the lat-
ter clip is stopped in position for clenching.
- 20 12. The method which comprises conducting a
plurality of connected unclenched clips to a
clenching station, clenching the foremost clip
about a strand, removing this clenched clip from
25 the clenching station by pulling the strand to
advance the adjacent unclenched clip into posi-
tion for clenching, stopping the latter clip in this
position and pulling on the strand to break the
connection between the clenched and unclenched
clips.
- 30 13. The method which comprises conducting a
plurality of connected unclenched clips to a
clenching station, clenching the foremost clip
about a strand, removing this clenched clip from
35 the clenching station by pulling the strand to
advance the adjacent unclenched clip into posi-
tion for clenching at the clenching station, stop-
ping the latter clip in this position and exerting
a pulling force on the clenched clip to break the
connection between the latter clip and the un-
40 clenched clip.
14. The method which comprises conducting a
plurality of connected unclenched clips to a
clenching station, clenching the foremost clip
about a strand, advancing the clips to remove the
45 clenched clip from the clenching station and to
bring an unclenched clip into this station, stop-
ping the latter clip in this station and exerting a
pulling force on the clenched clip to break the
connection between the latter and the clip to be
50 clenched.
15. The method which comprises conducting a
plurality of connected unclenched clips to a
clenching station with the endmost clip disposed
in said station, clenching the endmost clip about
55 a strand, advancing the clips to remove the
clenched clip from the clenching station and to
bring an unclenched clip into this station, stop-
ping the latter clip in this station by engaging at
least one of the projecting prongs thereof, and
60 while so engaging at least one of said prongs
exerting a pulling force on the clenched clip to
break the connection between the latter clip and
the clip to be clenched.
16. A machine of the class described, compri-
65 sing a single needle having a strand guiding por-
tion, a member providing a passage to receive the
needle, means to effect relative movement of the
needle and said member toward and away from
each other so that the needle may insert a strand
70 end into the passage, retaining means actuatable
to grip the strand end and effective to hold the same
as the needle is withdrawn from the passage, a
presser member effective to hold material over the
passage for penetration by the needle as the
75 needle is received by the passage, said presser mem-
ber being releasable upon each withdrawal of the
needle to permit the material to be drawn away
from the needle and the strand to be drawn
through said strand guiding portion and through
the material until two strand sections are juxtaposed
5 beyond the edge of the material, and uniting
means engageable by said strand sections, said
means being operable to join said juxtaposed sec-
tions while the needle remains withdrawn from
the passage and spaced from the uniting means,
10 the retaining means thereupon being releasable.
15 17. A machine of the class described, com-
prising a single needle having a strand guiding
portion, a member providing a passage to receive
the needle, means to effect relative movement of
the needle and said member toward and away
from each other so that the needle may insert a
strand end into the passage, retaining means actuatable
to grip the strand end and effective to hold
the same against the side of the passage as the
needle is withdrawn from the passage, a presser
member effective to hold material over the pas-
sage for penetration by the needle as the needle is
received by the passage, said presser member be-
ing releasable upon each withdrawal of the needle
25 to permit the material to be drawn away from the
needle and the strand to be drawn through said
guiding portion and through the material until
two strand sections are juxtaposed beyond the
edge of the material, and uniting means carried
30 by said member adjoining said passage and being
engageable by said strand sections, said means
being operable to join the juxtaposed strand sec-
tions while the needle remains withdrawn from
the passage and spaced from the uniting means,
35 the retaining means thereupon being releasable,
and a cutter effective to cut the strand portion
extending from the needle.
- 40 18. A machine of the class described, compris-
ing a single needle having a strand guiding por-
tion, a member providing a passage to receive the
needle, means to effect relative movement of the
needle and said member toward and away from
45 each other so that the needle may insert a strand
end into the passage, retaining means actuatable to
grip the strand end and effective to hold the same
as the needle is withdrawn from the passage, a
presser member effective to hold material over the
50 passage for penetration by the needle as the need-
le is received by the passage, said presser member
being releasable upon each withdrawal of the
needle to permit the material to be drawn away
from the needle and the strand to be drawn
55 through said strand guiding portion and through
the material until two strand sections are juxtaposed
beyond the edge of the material, and uniting
means engageable by said strand sections, said
means being operable to join said juxtaposed sec-
tions while the needle remains withdrawn from
60 the passage and spaced from the uniting means,
the retaining means thereupon being releasable,
the means which effects relative movement of
said member and needle being again actuatable to
operate said uniting means.
- 65 19. A machine of the class described, compris-
ing a needle having a strand guiding portion, a
member providing a passage to receive the needle,
means to effect relative movement of the needle
and said member toward and away from each
70 other so that the needle may insert a strand end
into the passage, retaining means actuatable to
grip the strand end and effective to hold the same
as the needle is withdrawn from the passage,
a presser member effective to hold material over
75 the passage for penetration by the needle as the
needle is received by the passage, said presser mem-

- needle is received by the passage, said presser member being releasable as the needle and member move away from each other to permit the material to be drawn away from the needle and 5 the strand to be drawn through said strand guiding portion and through the material until two strand sections are juxtaposed beyond the edge of the material, uniting means engageable by said strand sections, said means being operable upon 10 each withdrawal of the needle to join said juxtaposed sections, the retaining means thereupon being releasable, and means to feed a series of clips to said uniting means, said last-named means being effective to clench a clip about the 15 juxtaposed strand sections.
20. A machine of the class described, comprising a needle having a strand guiding portion, a member providing a passage to receive the needle, means to effect relative movement of the needle 20 and said member toward and away from each other so that the needle may insert a strand end into the passage, retaining means actuatable to grip the strand end and effective to hold the same as the needle is withdrawn from the passage, a 25 presser member effective to hold material over the passage for penetration by the needle as the needle is received by the passage, said presser member being releasable as the needle and member move away from each other to permit the 30 material to be drawn away from the needle and the strand to be drawn through said strand guiding portion and through the material until two strand sections are juxtaposed beyond the edge of the material, uniting means engageable by 35 said strand sections, said means being operable to join said juxtaposed sections, the retaining means thereupon being releasable, and means to feed a series of clips to said uniting means, said last-named means including an abutment 40 having an opening arranged to stop the first clip of the series, said means also providing jaws movable to clench the first clip about the juxtaposed strands, the opening permitting a clenched clip to pass therethrough whereby the succeeding 45 clip may be drawn into engagement with said abutment.
21. A machine of the class described, comprising a needle having a strand guiding portion, a member providing a passage to receive the needle, 50 means to effect relative movement of the needle and said member toward and away from each other so that the needle may insert a strand end into the passage, retaining means actuatable to grip the strand end and effective to hold the same as the needle is withdrawn from the passage, a 55 presser member effective to hold material over the passage for penetration by the needle as the needle is received by the passage, said presser member being releasable as the needle and member move away from each other to permit the material to be drawn away from the needle and the strand to be drawn through said strand guiding portion and through the material until two strand sections are juxtaposed beyond the edge 60 of the material, uniting means engageable by said strand sections, said means being operable to join said juxtaposed sections, the retaining means thereupon being releasable, and means to feed a series of clips to said uniting means, said last- 65 named means including an abutment having an opening arranged to stop the first clip of the series, said means also providing jaws movable to clench the first clip about the juxtaposed strands, the opening permitting a clenched clip 70 to pass therethrough whereby the succeeding clip 75

may be drawn into engagement with said abutment, said member providing a recess with converging sides to receive the juxtaposed strands and guide them to the opening in the abutment member and between the jaws whereby they may 5 be gripped by the clenched clip.

22. A manually operable device of the class described comprising a frame, a handle extending therefrom, a second handle pivoted to the frame, linkage connected to the second handle, a 10 needle supported by the frame and movable relative thereto, said needle having a strand guiding passage, said linkage being effective in causing relative movement of the needle and frame, said frame providing a passage to receive the needle 15 and the free end of a strand carried thereby, retaining means concomitantly actuatable to grip the strand end and to hold the same in the passage as the needle is withdrawn from the passage, a presser member movable concomitantly with the 20 needle to press material against a part of the frame and hold the same in the path of the needle as the same advances towards the passage so that the strand is passed through the material, said presser member being releasable as the 25 needle is withdrawn from the material so that the material may be pulled away from the frame to cause the strand to slide through the passage in the needle and through said material until two strand sections are brought into juxtaposition 30 beyond the edge of the material, and means carried by the frame to unite such juxtaposed strand ends, said means being actuatable by a portion of said linkage in response to a second relative movement of said handles. 35

23. A manually operable device of the class described comprising a frame, a handle extending therefrom, a second handle pivoted to the frame, linkage connected to the second handle, a needle supported by the frame and movable relative 40 thereto, said needle having a strand guiding passage, said linkage being effective in causing relative movement of the needle and frame, said frame providing a passage to receive the needle and the free end of a strand carried thereby, retaining means concomitantly actuatable to grip the strand end and to hold the same in the passage as the needle is withdrawn from the passage, a presser member movable concomitantly with the 45 needle to press material against a part of the frame and hold the same in the path of the needle as the same advances towards the passage so that the strand is passed through the material, said presser member being releasable as the needle is withdrawn from the material so that the material may be pulled away from the frame to cause the strand to slide through the passage in the needle and through said material until two strand sections are brought into juxtaposition 50 beyond the edge of the material, a uniting means supported on said frame and arranged to receive successive clips, said frame providing a recess to guide the juxtaposed strands into engagement with the first clip of the series, said uniting means being effective in clenching such 55 a grip about the juxtaposed strands. 60

24. A manually operable device of the class described comprising a frame, a handle extending therefrom, a second handle pivoted to the frame, linkage connected to the second handle, a needle 70 supported by the frame and movable relative thereto, said needle having a strand guiding passage, said linkage being effective in causing relative movement of the needle and frame, said frame providing a passage to receive the needle 75

- and the free end of a strand carried thereby, retaining means concomitantly actuatable to grip the strand end and to hold the same in the passage as the needle is withdrawn from the passage, a
- 5 5 presser member movable concomitantly with the needle to press material against a part of the frame and hold the same in the path of the needle as the same advances towards the passage so that the strand is passed through the material,
- 10 10 said presser member being releasable as the needle is withdrawn from the material so that the material may be pulled away from the frame to cause the strand to slide through the passage in the needle and through said material until two
- 15 15 strand sections are brought into juxtaposition beyond the edge of the material, a reel pivotally connected to the first-named handle and arranged to support windings consisting of a paper strip with juxtaposed metal clips, guide means
- 20 20 associated with said handle to receive a run of the paper strip with clips thereon, and a uniting means mounted on said frame and arranged to receive the first clip from said run, said uniting means including relatively movable jaws to
- 25 25 clench a clip about the juxtaposed strands and providing an opening through which the strands and the clenched clip may be drawn so that a succeeding clip may be positioned between the jaws.
- 30 30 25. The combination of opposed members, a single needle carried by one of said members, the other of said members being spaced from the needle to receive material to be ticketed, the latter member having a passage to receive the
- 35 35 needle and the strand carried thereby, yieldable means for holding superposed pieces of material against the latter member in the path of the needle, means for effecting relative movement of said members toward and from each other for
- 40 40 passing the needle and its strand through the material and into said passage and for withdrawing the needle, retaining means for holding the strand in said passage as the needle is withdrawn, means operable while the needle remains
- 45 45 in withdrawn position and following each withdrawal of the needle for uniting portions of the strand disposed between said passage and the needle, said retaining means being releasable after operation of said uniting means, and a cutter operable to sever the strand section extending from the uniting means to the needle, said cutter being operable as the retaining means is released.
- 50 50 26. A hand device of the class described comprising a frame, a needle supported by the frame and having a strand receiving passage so that a strand threaded through the passage may have an end projecting from the needle, the frame providing a recess with converging sides, a clip feeding mechanism mounted on said frame for feeding an open clip to the inner part of said recess, so that, when the needle is advanced through sheet material, the strand end may be gripped and the material may manually be drawn
- 55 55 away from the needle and the gripped end to bring strand sections extending from opposite sides of the material into juxtaposition in the open clip, clenching mechanism carried by said frame for closing the clip, a cutter movably mounted on said frame and operable to sever the

strand between the clip and the needle so that a strand end is left projecting from the needle to be passed through another piece of sheet material, and a movable handle connected to the frame, the clenching mechanism and cutter being operably connected to the handle for concomitant operation by a single movement of the handle. 5

27. A hand device of the class described comprising a frame, a needle on said frame, said needle being movable to advanced and retracted positions and having a strand-receiving passage, a clip supplying mechanism carried by said frame, said frame providing a recess having converging walls, means to hold an open clip in a 15 position to receive juxtaposed strand sections when the latter are guided into the clip by said converging walls, a movable handle, clenching mechanism on said frame for closing the clip on the strand sections, a cutter on said frame, said mechanism and cutter both being operably connected to the handle for actuation in response to a single movement of the handle, said needle being arranged so that it may penetrate and carry a strand end through a sheet article so 25 that the strand end may then be gripped, whereupon the needle may be retracted from the material and the material may be manually moved away from the gripped end and the needle to bring two strand sections into juxtaposition, said sections being manually movable into the open clip, the handle then being operated to clench the clip and sever the strand section between the clip and needle to leave a strand end projecting from the needle for advance movement 30 through another sheet article. 35

28. A hand device of the class described comprising a frame, a needle on said frame, said needle being movable to advanced and retracted positions and having a strand-receiving passage, means on the frame to supply a strand for movement through said passage, a clip supplying mechanism carried by said frame, the end of the frame providing a recess having converging walls and means to hold an open clip in a position to 40 receive juxtaposed strand sections when the latter are guided into the clip by said converging walls, means on the frame to supply successive open clips to said position, a movable handle, clenching mechanism on said frame for closing 45 the clip on the strand sections, a cutter movably mounted on the frame substantially between the recess and the retracted needle, said mechanism and cutter both being operably connected to said handle and being actuatable in response to a single 50 movement of the handle, said needle being arranged so that it may penetrate and carry a strand end through a sheet article so that the strand end may then be gripped, whereupon the needle may be retracted from the material and 55 the material may be manually moved away from the gripped end and the needle to bring two strand sections into juxtaposition, said sections then being manually movable into the open clip, the handle then being operated to clench the 60 clip and sever the strand section between the clip and needle to leave a strand end projecting from the needle for advance movement through another sheet article. 65
